UNITED STATES. PATENT OFFICE.

HARRY WILLIAMS, OF VANCOUVER, BRITISH COLUMBIA, CANADA.

PERMUTATION PADLOCK.

1,413,209.

Specification of Letters Patent. Patented Apr. 18, 1922.

Application filed February 2, 1921. Serial No. 441,841.

To all whom it may concern:

Be it known that I, HARRY WILLIAMS, a subject of the King of Great Britain, and a resident of the city of Vancouver, in the 5 Province of British Columbia, Canada, have invented certain new and useful Improvements in Permutation Padlocks, of which the following is a specification.

My invention relates to improvements in 10 locks, of the permutation type, and the object of my invention is to provide a device of this nature which is simple in construction having a minimum number of parts so that it can be manufactured and sold at a 15 low cost while fulfilling with equal facility and efficiency the functions of more expensive locks and at the same time being capable of a wide range of different combinations.

I attain this object by the construction 20 illustrated in the accompanying drawings in which—

Fig. 1 is a view of the lock, in side elevation.

Fig. 2 is a plan view.

25 Fig. 3 is a detail view of the alphabetical disc.

Figs. 4, 5 and 6 are detail views of the combination discs.

Figs. 7 and 8 are views of the operating 30 shaft and operating shaft sleeve respectively.

Fig. 9 is an inside view of one half of the lock casing.

Fig. 10 is an inside view of the opposite 35 half of the lock casing.

Fig. 11 is a side view of the bolt.

Fig. 12 is an edge view.

Fig. 13 is a plan view of the lock, in part section.

40 Similar figures of reference indicate similar parts throughout the several views.

The lock consists of a casing constructed preferably of two plates 1 and 2, as shown in Figs. 9 and 10 respectively, these plates 45 being secured together by riveting or in any other approved manner. The upper, lower, and end edges of the plates are flanged inwardly, as at 3—4—5—6 and 7—8—9 and 10 respectively, which flanges meet when the

50 plates are assembled together so as to form a casing in which the working parts, herein-after mentioned, are completely enclosed, and in the upper and lower flanges of this casing openings 11—12 and 13—14 are provided, in which openings are slidably mount-

ed the side bars 15 and 16 of the locking shackle 17, the bars 15 and 16 being slotted as at 18 and 19 respectively, as shown in Fig. 1. A square aperture 20 is provided in plate 1 in which extends the end of a square 60 sleeve 21 which extends within the casing to within a short distance of the plate 2 and which sleeve is provided with a round bore 22 in which is rotatably mounted the operating shaft 23, the inner end of which shaft 65 is turned and supported in a recess 24 formed on the inner face of the plate 2 while its outer end is extended exteriorly of the plate 1 and provided with a knurled head 25. The shaft 23 where it projects 70 through the sleeve 21 is squared, as at 26, and on this squared portion is fitted a circular disc 27 on the outer face of which are arranged annularly the letters of the alphabet and on its inner face the disc 27 is provided with a pin 28, which pin extends through slots 29, 30 and 31 formed respectively in discs 32, 33, and 34, these discs being arranged side by side on the sleeve 21, and being separated from each other by 75 suitable washers 35 so as to keep the discs free from the frictional contact with each other. The three discs 32, 33 and 34 and the alphabetical disc 27 are each provided with a notch, 36, 37, 38 and 39 respectively, as 80 shown, and their peripheries lie close to the bars 15 and 16 of the shackle 17. Disc 27 is made slightly larger in diameter than discs 32, 33, and 34 and this disc 27 is also provided with notches 39^a spaced equidistantly around its periphery, the bottoms of which notches are in alignment with the peripheries of the discs 32, 33, and 34, these notches being provided to disguise, as it were, the true position of the opening 95 notches 36, 37, 38, and 39, and prevent "feeling out" the combination, since the bolt can drop into any one of the notches 39^a and without indicating which notch is the correct one, that is, 39, to anyone not knowing the combination. The inner end of shaft 23 is riveted over slightly on the disc 27 to prevent withdrawal of the shaft after assembling.

40 indicates the bolt, formed of a flat bar 105 adapted to fit slidably in a groove 41 formed in the inside face of the plate 1, the bar lying flush with the plate and being provided with a slot 42 so that it may be fitted over the sleeve 21. The bar adjacent its inner end is 110

provided with a tongue 43 which extends transversely of the casing between the peripheries of the discs and the side bar 15 of the shackle 17, while its other end is reduced as at 44 and extended exteriorly of the casing and turned over on its outer end, as at 45, so that it can be gripped and pulled outwardly when unlocking the lock, as herein-after described. The reduced end 44 of the 10 bolt is provided with a thickened portion 47 adapted to fit the slot 19 in the bar 16 when the device is locked. 46 indicates an opening in plate 1 through which the letters on the disc 27 may be seen.

15 The operation of the lock may be briefly described as follows, it being understood that in any one lock a predetermined combination of letters is arranged together with predetermined lengths of slots in the discs 20 which when actuated as directed will bring all the notches 36, 37 and 38 and 39 into alignment and that when locked the tongue 43 is engaged in the slot 18 of the bar 15, the tongue 43 being prevented from disengagement 25 from the slot by the peripheries of the discs, which lie close to the bar 15. Now, to unlock, the alphabetical disc is turned in the specified direction by means of the head 25 to bring the letters of the combination in 30 succession to the opening 46, at the completion of which operation the notches will be in line with each other opposite the tongue 43, which may then be drawn out of the slot 18 into the notches by pulling on the end 45, 35 allowing the locking shackle to be withdrawn. For instance, suppose, the combination in this case is AB, W, and F; then the head 25 would be rotated to first bring AB to the opening 46, then back to bring W to the 40 opening and finally in the opposite direction to bring F to the opening, when the lock would be ready to open. The locking is effected by pushing in the bolt to replace the tongue in slot 18 and then turning the head 45 25 a few times to destroy the combination setting and disarrange the aligned position of the notches.

What I claim as my invention is:—

1. A lock comprising a casing having an 50 aperture on one side, a locking staple slideable in said casing one bar of which is notched, an operating shaft within the casing extending exteriorly thereof and provided with a head, an index disc secured to

the inner end of the said shaft the index of 55 which is observable at the casing aperture, said disc having a peripheral notch and a pin on its inner face, a non-rotatable sleeve through which said shaft extends, a plurality of discs rotatably mounted on said sleeve 60 notched on their peripheries each provided with curved slots of varying length through which the said pin extends whereby rotation of the pin in the opposite directions alternately rotates the disc to bring the respective 65 notches into alignment one with the other, and a bolt having a tongue seated in the staple notch and normally held against withdrawal by the disc peripheries, the withdrawal of the tongue being rendered possible 70 by the aligning of the notches.

2. A lock comprising a locking staple both bars of which are notched, a plurality of discs rotatably mounted between the bars of the staple each having a peripheral notch, a 75 withdrawable bolt having a tongue seated in the staple notch and an enlargement seated in the other staple notch and held against withdrawal by the said discs, and means for rotating said discs independently to bring their 80 notches into alignment one with the other and with the said tongue.

3. A lock comprising a casing having an aperture on one side, a notched locking staple slideable in said casing, an operating 85 shaft within the casing, extending exteriorly thereof and provided with a head, an index disc secured to the inner end of said shaft the index of which is observable at the casing aperture, said disc having a peripheral notch 90 and a pin on its inner face, a non-rotatable sleeve through which said shaft extends, a plurality of discs rotatably mounted on said sleeve notched on their peripheries each provided with curved slots of varying length 95 through which the said pin extends whereby rotation of the pin in opposite directions alternately rotates the discs to bring the respective notches into alignment one with the other, said discs being of less diameter than 100 the index disc, and a bolt adapted to co-act with the notched staple held normally against withdrawal by the disc peripheries the withdrawal of which is rendered possible by the aligning of the said disc notches.

Signed at Vancouver, B. C., Canada, this 24th day of January, 1921.

HARRY WILLIAMS.
